UNITED STATES PATENT OFFICE.

PAHR ANDERSON, OF CAMBRIDGE, MASSACHUSETTS, ASSIGNOR TO DOVER STAMPING & MANUFACTURING COMPANY, OF PORTLAND, MAINE, A CORPORATION OF MAINE.

SAFETY-CAN.

1,312,822.

Specification of Letters Patent. Patented Aug. 12, 1919.

Application filed May 13, 1916. Serial No. 97,413.

To all whom it may concern:

Be it known that I, PAHR ANDERSON, of Cambridge, in the county of Middlesex and State of Massachusetts, a citizen of the 5 United States, have invented a new and useful Improvement in Safety-Cans, of which the following is a specification.

My invention relates especially to that type of can used for the storage of gasoline 10 or other liquids which give off inflammable gases. The invention has for its object the providing of a can which has automatic means for closing the spout and keeping the same closed in whatever position the can 15 may be placed, and requiring positive action to open the closure in order to pour out the liquid.

Due to its inflammable nature it has been 20 found necessary to store gasoline in receptacles having tight-fitting stoppers and the ordinary type of can used in garages and like places, where such liquids are used, commonly has a cork or wood plug. This plug, unless driven in, is never very tight and as 25 a result there is apt to be a leakage of gas, or in the event of the can being overturned, it is comparatively easy for the plug to be dislodged. With this in mind, I have provided a can in which there can be no leakage 30 of gas and in case of the can being overturned the contents will be securely confined unless the closure is opened. Utilizing the theory that flame will not pass through wire gauze to explode a gas, I have provided an 35 additional safeguard against the possibilities of combustion as the liquid is poured out by means of a strainer through which the liquid must pass when the spout is opened.

40 My invention and the particular features thereof will best be understood from the drawings, in which—

Figure 1 is a vertical section of a can embodying my invention.

45 Fig. 2 is a top view.

Fig. 3 is a view at right angles to Fig. 1 showing the bail stops.

50 A is the body of the can which as shown is cylindrical in shape with a flat bottom B and a top C which is convex or dome-like in form. The top C is provided with a closure c preferably made of brass located at the apex of the dome. To the body of the can is fastened the bail D by means of

ears d. Each ear is provided with a projection or lip d¹ limiting the fall of the bail D by gravity toward the side from which the closure cap is operated. This is for a purpose to be hereinafter explained. The closure c is in the form of a flanged 55 spout, being fastened to the top of the can by means of the flanged portion c¹. The spout portion c² serves also as a filling opening. The spout casting has two wings c³ which form a casing for the automatic closing mechanism. The top of the spout is slightly beveled as at c⁴ and provides a seat for the cap E. This cap E fits over the beveled portion of the spout and for this purpose is recessed as at e. To fit this recess 60 is a circular gasket e¹ which is held in place by a washer e² supported by a screw e³. Pivoted to the hinge pin f mounted in the wings c³ is the handle F. The inner end of the handle F is provided with a segmental 65 gear f¹ located on its upper surface. At the top of the cap E there is a projection e⁴ by which the cap is pivoted by means of the pin e⁵ to the lever arm G. This lever arm G projects forward slightly beyond the 70 edge of the cap as at g to limit the rocking of the cap about its pivot. The lever arm is curved as at g¹ and is pivoted upon a hinge pin g² mounted between the wings c³. On the under side of the inner end of this 75 lever arm is a segmental gear g³ which is adapted to mesh with the gear f¹, the location of the hinge pins f, g² being arranged accordingly for this purpose. To hold the cap normally in a closed position a heavy 80 bronze spring H is looped over the lever arm G as at h and wound around the axis of said lever arm, the ends bearing against the spout casting in the corners formed by the wings c³.

95 To open the cap the handle F is raised against the force of the spring, the cap remaining open only so long as the handle is held in its elevated position and when released, the force of the spring automatically 100 returns the cap to its closed position. Inasmuch as the force of the spring is very great, it is found somewhat difficult to raise and hold the lever handle F without additional assistance. To this end the bail D is utilized in its normal position when resting against the stops or projections d¹ so that its position, to which it will naturally fall 105

by gravity, closely corresponds to or registers with that in which the handle F is normally held by the spring H; and thus both the bail and the handle may be grasped 5 together by the hand and a sufficient grasping hold is obtained to lift the handle easily and hold the cap open against the force of said spring. Near the bottom of the can is a suitable handle K to facilitate raising and 10 tipping the can to pour out its contents.

The inner end of the spout c² extends downward into the can as at c⁵ and has exterior threading c⁶. By means of a screw coupling J, which has threaded connection 15 with the threading c⁶ of the interior projection of the spout, a strainer preferably of brass gauze J¹ is attached to the spout. This strainer extends vertically downward to a point near the bottom of the can, a strap j 20 being placed within the can through which the strainer passes to hold it in a perpendicular position. The upper end of the strainer flanges outwardly as at j¹ to fit about the end of the spout and the screw 25 coupling J has an inside shoulder J² which clamps this edge of the strainer tightly to the spout.

The advantages of this invention will particularly appeal to those skilled in the art, 30 for so far as I am aware the present device has never been employed to prevent combustion of the inflammable gases. I do not intend to limit myself to the precise construction shown for many variations may be 35 employed and yet be within the scope of my invention.

What I claim as my invention is:—

1. A safety can consisting of a closed receptacle comprising a top, a spout fixed to 40 said top and having integral wings at one side thereof, a handle lever pivotally mounted between said wings and having a geared portion, a bent lever arm also mounted between said wings and also having a geared 45 portion meshing with the geared portion of said lever, a closing cap for said spout carried by said lever arm and a spring co-acting with said lever-arm and lever to hold said cap normally closed and to retain said lever in a lowered position from which it will be lifted when said cap is to be removed to open said spout.

2. A safety can consisting of a closed receptacle comprising a top, a spout having a 55 flanged portion by which it is fixed to said top and having integral wings at one side thereof, a handle lever pivotally mounted between said wings and having a geared portion, a bent lever arm also mounted between 60 said wings and also having a geared portion meshing with the geared portion of said

lever, a closing cap for said spout carried by said lever arm and a spring co-acting with said lever-arm and lever to hold said cap normally closed and to retain said lever in a lowered position from which it will be lifted when said cap is to be removed to open said spout. 65

3. A safety can consisting of a closed receptacle comprising a top, a spout fixed to 70 said top and having integral wings at one side thereof, a handle lever pivotally mounted between said wings having a geared portion, a bent lever arm also mounted between said wings and also having a geared portion 75 meshing with the geared portion of said lever, a closing cap for said spout pivotally attached to said lever arm, means for limiting the rocking movement of said lever arm relative to said cap, and a spring co-acting 80 with said lever-arm and lever to hold said cap normally closed and to retain said lever in a lowered position from which it will be lifted when said cap is to be removed to open said spout. 85

4. A safety can consisting of a closed receptacle comprising a top, a spout fixed to said top and having integral wings at one side thereof, a handle lever pivotally mounted between said wings and having a geared 90 portion, a bent lever arm also mounted between said wings and also having a geared portion meshing with the geared portion of said lever, a closing cap for said spout carried by said lever arm, a spring co-acting 95 with said lever-arm and lever to hold said cap normally closed and to retain said lever in a lowered position from which it will be lifted when said cap is to be removed to open said spout, a pivoted bail attached to said 100 can, and stop means for limiting the downward movement of said bail by gravity so as to hold it in a position closely corresponding to that of the normal position of said handle lever so that both may be conveniently grasped by one hand and thus be lifted together. 105

5. A safety can consisting of a closed receptacle having a spout, combined with a spring-pressed cap for closing said spout, 110 a lever handle connected with said cap and by the operation of which lever handle said cap may be opened against the stress of its closing spring, a pivoted bail attached to said can and stop means for limiting the 115 downward movement of said bail by gravity so as to hold it in a position closely corresponding to that of the normal position of said lever handle so that both may be conveniently lifted together.

PAHR ANDERSON.
